UNITED STATES PATENT OFFICE.

EDWARD HAMMANN, OF BROOKLYN, NEW YORK, ASSIGNOR TO THE
J. L. MOTT IRON WORKS, OF NEW YORK, N. Y.

SUPPLY-CONNECTION FOR BASINS OR BATHS.

SPECIFICATION forming part of Letters Patent No. 449,880, dated April 7, 1891.
Application filed September 20, 1890. Serial No. 365,620. (No model.)

To all whom it may concern:

Be it known that I, EDWARD HAMMANN, a citizen of the United States, residing in Brooklyn, in the county of Kings and State of New York, have invented an Improvement in Hot and Cold Water Supply Connections for Basins, Baths, &c., of which the following is a specification.

Bath and basin connections have before been made in which either hot or cold water, or a mixture of the two, can be delivered by one nozzle or bib into the bath or basin, and in these cases the cocks or valves for regulating the water have sometimes been below or behind the bath or basin and in other instances they have been above the slab.

The object of the present invention is to simplify the mode of construction and to facilitate the connection of the respective devices to the slab, and at the same time to combine with the hot and cold water supply pipes and cocks a stand-pipe and overflow that serve as a foundation or support for the respective parts that supply and regulate the hot and cold water.

In the drawings, Figure 1 is a vertical section through the nozzle or bib and the stand-pipe. Fig. 2 is an elevation partially in section, and Fig. 3 is a sectional plan at the line xx .

The hot-water valve or cock A and cold-water valve or cock B are to be of any desired construction. Usually they are what is known as a "globe-valve," the water-supplying pipes being connected by couplings at the lower ends, as seen at 2 and 3, and the water passes off laterally above the valve by the pipes C C' to the hollow water-way D, from which rises the mixing-column E, that passes through the slab or plate F surrounding the upper part of the bath-tub, or beneath which the basin is attached; and there is a bib or nozzle G the under surface of which may rest upon the top of the slab F, and the end is turned downwardly into the bath or basin, and the top end of the mixing-column E passes into the bottom of this bib, and is screwed or otherwise permanently fastened thereto, and it is usually preferable to pass the lower end of the mixing column E through the hollow water-way D and fasten the lower end thereof by the nut 4, there being washers between the nut and

the surface of the water-way and a collar at 5 around such mixing-column E. The pipes C and C' are preferably made with the water-way D, and screwed at their ends to the hot and cold water cocks, respectively. The caps 6 of the respective hot and cold water valves A B are tubular and extend around the stem 7 up to the sockets 8 that pass through the slab F, and there are flat rings or disks H below the flanges of the sockets 8 and resting upon the slab F, which rings are usually marked with the word "Hot" or "Cold" to indicate the temperature of the water, and upon the upper ends of the stems 7 are the hand-wheels I, by which the stems are turned to admit or exclude water by the respective valves.

In cases where a stand-pipe and overflow is not used in connection with the cocks, pipes, and bib described, it is preferable to make use of lock-nuts beneath the slab and around the mixing-column E and the tubular portions of the caps 6, to clamp the respective parts to the slab, as at S; and I remark that these parts, thus far described, are easily constructed and attached either to the slab of the basin or to the rim or plate of the bath-tub, and the parts are highly ornamental; but the parts that are above the slab are neither large nor numerous, hence there is but comparatively little area or surface that requires to be plated and finished in the manner now usual with the best class of work.

When a stand-pipe and overflow is made use of in connection with the parts heretofore described, the water-way D is usually semi-circular to partially surround the stand-pipe K and be steadied thereby, and there is a tubular coupling L, into which the upper end of the stand-pipe K is screwed, and which tubular coupling L passes through the slab F and is held in place by a lock-nut 10, and to obtain a more ornamental finish and to support the nozzle or bib G, I usually extend such nozzle or bib in the form of a ring G' around the tubular coupling L, so that such ring G' is firmly held to the surface of the slab by the flange 11, resting upon such ring G' and being pressed thereto by screwing up the lock-nut 10.

The stand-pipe K is to be provided with a

connection at the lower end to the waste-pipe or drain, and there is also usually a lateral connection to the bottom of the basin or bath-tub, as seen at N, and within the stand-pipe 5 is an overflow-pipe P, having a valve 12, around the lower part thereof, which rests upon a seat below the lateral pipe N and serves to retain water in the basin or bath until the overflow-pipe is elevated, and this 10 overflow-pipe P has holes in it at the level at which the water is to stand, and the pipe extends up through the tubular coupling L, and there is a cap Q at its upper end and a slot and pin by which the overflow-pipe can be held up while the water is running out of the 15 bath or basin. This stand-pipe, overflow-pipe, valve, and cap are similar to those represented in the patent of John Demarest, No. 358,147; or such stand-pipe and overflow-pipe 20 might be similar to those represented in the patent of W. S. Carr, No. 170,709. This fixture, as a whole, is very neat, artistic, easily kept clean, and projects but little above the slab.

25 It will be apparent that in consequence of the mixing-column E passing into the hollow water-way D and having lateral openings for the water to pass from the water-ways into the column, and being held by the removable 30 nut 4, the hot and cold water valves can be disconnected from the mixing-column and the bib by simply removing the nut 4 without disturbing any of the other parts of the apparatus. This is a convenience, because it 35 allows the cocks or valves, or either of them, to be separated for grinding or repairing, as may become necessary from time to time. It will also be apparent that the tubular coupling L may be formed with the stand-pipe K 40 or permanently fastened thereto, and the ring G' may be of any desired ornamental shape to surround the upper part of the stand-pipe and be held by the flange 11 when the nut 10 is screwed up against the under side of the 45 slab.

Above the bib and supported by the same or by the mixing-column, there is a fixed cup R, that is adapted to the reception of rings or jewelry, and as this is a rigid fixture there is no 50 risk of an article placed therein being shaken out in moving either valve or the overflow-pipe.

I claim as my invention—

1. The combination, with the bib or nozzle G and the mixing-column E therewith con-

nected and passing down through the slab, of the hot and cold water valves, the water-ways connecting the respective valves, there being an opening through the water-way D for the mixing-column E to pass through, the collar 60 5 around the mixing-column, and the nut 4, screwed to the lower end thereof for confining the parts in position, the mixing-columns having holes through the same opening into the water-way D, substantially as set forth. 65

2. The combination, with the hot and cold water valves and the connecting water-ways between the same, of the mixing-column and the bib or nozzle above the slab, the stand-pipe K, the tubular coupling at the upper end 70 thereof, and the lock-nut for connecting the stand-pipe permanently with the slab and for holding the bib or nozzle to such slab, substantially as set forth.

3. The combination, with the hot and cold 75 water supply valves and pipes, of the bib or nozzle adapted to rest upon the top of the slab and having a ring extending from the rear end of such bib or nozzle, and the stand-pipe and its coupling passing through the slab and 80 through the said ring and holding the same in position, substantially as set forth.

4. The combination, with the hot and cold water valves and the connecting water-ways between the same, of the mixing-column and 85 the bib or nozzle above the slab, the stand-pipe K, opening through such slab and connected therewith, and the overflow-pipe within the stand-pipe, substantially as set forth.

5. The combination, with the hot and cold 90 water valves and the connecting water-ways between the same, of a mixing-column and a bib or nozzle above the slab and connected with the mixing-column, the stand-pipe K passing through the slab and holding the bib 95 in position, substantially as set forth.

6. The combination, with the hot and cold water supplying valves and pipes, of the bib or nozzle adapted to rest upon the top of the slab and having a ring extending from the rear end of such bib, the stand-pipe passing through the slab and through the ring and the collar for holding the ring in position, substantially as set forth.

Signed by me this 17th day of September, 1890.

EDWARD HAMMANN.
